CLAIM

The ornamental design for a camera, as shown and described.

DESCRIPTION

FIG. 1 is a top, rear and left side perspective view of a camera showing our new design;

FIG. 2 is a top plan view thereof;

FIG. 3 is left side elevational view thereof;

FIG. 4 is right side elevational view thereof;

FIG. 5 is front elevational view thereof;

FIG. 6 is rear elevational view thereof;

FIG. 7 is a bottom plan view thereof; and,

FIG. 8 is bottom, front and right side perspective view thereof.

The broken lines shown in the drawings are for illustrative purposes only and form no part of the claimed design.
